UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

WATCH.

1,054,446.

Specification of Letters Patent.

Patented Feb. 25, 1913.

Application filed November 7, 1911. Serial No. 658,928.

To all whom it may concern:

Be it known that I, WILSON E. PORTER, a citizen of the United States, residing at New Haven, in the county of New Haven 5 and State of Connecticut, have invented a new and useful Improvement in Watches; and I do hereby declare the following, when taken in connection with the accompanying drawings and the letters of reference marked thereon, to be a full, clear, and exact description of the same, and which said drawings constitute part of this specification, and represent, in—

Figure 1 a view in front elevation of a 15 stop-watch constructed in accordance with my invention with the dial removed. Fig. 2 a broken sectional view on the line *a—b* of Fig. 1. Fig. 3 a detached view of the center-pinion showing the split or rear end of 20 its hollow shaft.

My invention relates to an improvement in watches, with the construction of stop-watches or chronographs particularly in view, though not limited to use in such 25 watches; the object being to provide dial-work of simple and cheap construction.

With these ends in view, my invention consists in a watch having certain details of construction and combination of parts 30 as will be hereinafter described and pointed out in the claim.

In carrying out my invention as herein shown, I cut the dial-pinion 2 directly upon the outer end of an arbor 3 which I shall 35 hereafter call the center-arbor on account of its correspondence to the center arbors of an ordinary watch, though in my watch it is not centrally located as the name would imply. Upon the said arbor 3 I mount a 40 wheel 4 which is impinged against the inner face of the said pinion 2. The said wheel 4 which I shall call the driving minute-wheel, is rotated once an hour. The center-arbor 3 as thus constructed with an 45 integral pinion 2 and furnished with the wheel 4, is shoved from front to rear through the hollow shaft 5 of the center-pinion 6, the said shaft 5 being journaled at its forward end in the front movement- 50 plate 7 and at its rear end in the rear movement-plate 8, and having mounted upon it the center-wheel 9 which is interposed between the said center-pinion 6 and the front movement-plate 7. For the purpose of securing 55 a friction fit between the arbor 3

and the hollow shaft 5, the latter is formed at its rear end, as shown in Fig. 3, with longitudinal slits 10 arranged opposite each other, the said arbor and shaft being constructed and proportioned so that when the 60 arbor is pushed into the shaft, the latter will be sprung enough at its split rear end to grip the arbor so that under all normal conditions the arbor, with its pinion 2 and wheel 4, will revolve with the shaft which 65 is driven in the usual manner from the time-train. In the stop-watch which I am now describing, the center-arbor 3 and its immediately related parts are, as already indicated, not located in the center of the movement in accordance with ordinary usage, but are located to one side of the center of the movement to give ample room at the center of the movement for the operation of the sweep-second hand shaft to which a 70 rocking motion is given in the usual manner. Therefore the driving minute-wheel 4 is meshed into a corresponding but driven minute wheel 11 having the same number of teeth, revolving once an hour, and provided with a hub 12 which receives the minute-hand which is not shown. The said wheel 11 turns upon a stud 13 mounted in the front movement-plate 7 and made hollow as usual for the reception of the sweep 75 second-hand arbor which is not shown. The center pinion 2 meshes into an hour-wheel 14 provided with a hub 15 to which the hour hand, also not shown, is applied, the hub 15 turning upon the hub 12 aforesaid. 80

The center pinion 2, the center arbor 3, and the wheel 4 are driven by the time-train on account of the friction grip of the hollow center-shaft 5 upon the arbor 3, but at the same time the friction thus secured 85 yields to permit the arbor 3 to revolve within the shaft 5 in shifting the hands for setting the watch.

I call particular attention to the fact that my improved watch structure entirely dispenses with a cannon pinion, that term being used in the art to designate a relatively long sleeve frictioned over a true center arbor for being driven thereby and carrying the minute wheel which in my improved 95 structure is loosely mounted upon the hub 12 of the wheel 11.

I claim:—

In a watch, the combination with the front and rear movement-plates thereof, of 110

6 a split hollow center-shaft journaled in the said plates at one side of the center of the watch and formed with an integral center-pinion, a center-arbor furnished at its front end with an integral center-pinion, and shoved from front to rear into the said split hollow center-shaft with which it is frictionally coupled, a driving minute-wheel mounted upon the said center-arbor,
10 10 a center-wheel mounted upon the split hollow center-shaft, a stud located at the center of the watch, a driven minute-wheel

turning upon the said stud and meshed into by the driving minute-wheel aforesaid, and an hour-wheel turning upon the hub of the 15 driven minute-wheel and meshed into by the said center-pinion.

In testimony whereof, I have signed this specification in the presence of two subscribing witnesses.

WILSON E. PORTER.
